VERNAN BAWLF, OF MALOTT, WASHINGTON

WATER WHEEL

Application filed May 25, 1927. Serial No. 194,150.

This invention relates to improvements in water wheels. The principal object of the invention is to provide a wheel of this character having radially extending vanes or rotors, and in which approximately one-half the number of rotors resist the current and cause a rotation of the wheel, while the other rotors offer no resistance to the current. An important feature of the invention is that 10 logs, chips or other debris floating with the current cannot contact with any of the rotors so as to injure the same or interfere with their operation. Another important feature is that a spillway is provided over which the 15 excess of water spills in its passage over the wheel. Another feature is that power can be taken off from the wheel by a shaft which may extend in any direction from the center of rotation of the wheel. I accomplish these 20 and other objects of my invention by the peculiar arrangement and combination of the parts as will be more fully hereinafter described and explained in the following specifications, shown in the accompanying 25 drawings and finally pointed out in the appended claims.

In the drawings:

- Fig. 1 is a plan view of the device with the cover removed.
- Fig. 2 is a sectional view taken upon the lines 2—2 of Fig. 1.
- Fig. 3 is a similar view taken upon the line 3—3 of Fig. 1.
- Fig. 4 is a plan of the cone.
- Fig. 5 is a sectional view of the cone taken upon the line 5—5 of Fig. 4.

Referring now more particularly to the drawings, reference numeral 1 indicates the side walls of a housing which is preferably formed of concrete. Bridging the side walls at the forward end is a cross member 2 from which downwardly and outwardly extend bars 3. The arrows in Fig. 3 indicate the direction of the flow of the current. 4 indicates the water lever. 5 indicates a cover which extends from one of the side walls 1 to the other. Extending upwardly from the floor is a cone shaped member indicated at 6. The cone is cut away as indicated at 7 so as to leave an upstanding ridge 8 or water baffle.

8—a indicates a similar baffle on the opposite side. 9 is a central shaft revolvably mounted in a seat 10 in the apex of the cone. 11 is a hub member from which radially and rigidly extend arms 12. 13 is a ring which is rigid with the side walls 1. Hinged at 13—a to each of the arms 12 is a vane 14 and to the lower edges of the vanes are similarly hinged flaps 15 whose lower edges are formed at an angle to correspond with the angle of the cone from its outer periphery to its apex. Rigidly extending from each of the arms 12 is a member 16 slotted at 17. Pivotally mounted within each of these slots is a trigger 18, the upper ends of all the triggers being in the path of an arm 19, secured by straps 20 to the member 2 and upon whose free end is a roller 21. Each of the arms 12 is secured at 22 to a ring 23 so that the rings and the arms form the wheel proper. The members 16 are bent as at 24 and at their extremities are rollers 25 which wipe upon the fixed ring 13 as the wheel revolves. When the wheel is in its position as shown in Fig. 1 it will be seen that the free ends of the rotors 14 contact with the inner surfaces of the side walls 1. 26 indicates chains one of each of whose ends is secured at 27 to a rotor 14 and its opposite end is secured at 28 to one of the arms 12 so that as the wheel is rotated in contra-clockwise direction as viewed in Fig. 1, by means of a thrust upon the upper-most rotor seen in that figure, the rotor is held against movement about its center 13—a in the direction of movement of the wheel, while the rotor just to the right of the one just described is free to collapse or fold up about its center 13—a as the wheel revolves in the direction stated. Friction of the parts is reduced to a minimum because of the rollers 25 as will be understood, although I prefer to arrange a ball race on the upper surface of the fixed rim 13 so as to still further reduce the friction. 29 is a pinion gear secured to the shaft 9 and with which a power conducting shaft, similarly equipped with a pinion wheel, may be connected so as to take off the power from the rotating shaft 9 in any direction radially from the shaft.

The operation of the device is that as the

current flows in the direction of the arrow in Fig. 2 it passes between the bars 3, thence onwardly against the forwardly inclined portion of the cone 6 against the baffles 8 and 8—a and in doing so all of the rotors 14 which are upon the left side of the device as seen in Fig. 1 resist the current and cause the wheel to rotate, while the rotors on the opposite side of the wheel collapse and allow the water to flow over the baffle 8 and thence outwardly through the open or rear end of the housing so that no resistance is offered by one-half of the number of baffles, while the other half offer resistance and cause the wheel to rotate. If logs, limbs or other debris are floating in the stream it is plain that they will ride up against the bars 3, over the top of the device and do no harm. Of course the uppermost rotor 14 as seen in Fig. 1 will be rather in a neutral position but it cannot be deflected to the right as seen in that figure because of the roller 21 which has at that time contacted with the upper end of the trigger 18 and moved it to its position as plainly seen in Fig. 3. After that time the chains 26 of course would prevent any rotation of that rotor 14 about its hinge point 13—a. Just before the uppermost rotor reached its position as seen in Fig. 1 it of course contacted with the upper edge of the water baffle 8 (see Fig. 3) allowing the water to flow between the upper edge of the baffle and the rotor.

While I have shown a particular form of embodiment of my invention, I am aware that many minor changes therein will readily suggest themselves to others skilled in the art without departing from the spirit and scope of my invention. I therefore desire to avoid being limited to the exact form of embodiment which I have herein shown and described.

Having described my invention, what I claim as new and desire to protect by Letters Patent, is:—

A water wheel including a rotor inclined to the level of the stream in which it is arranged, said rotor including arms, blades pivotally supported thereon, chains for holding the blades against movement in one direction, a fixed baffle to engage and feather the blades in the opposite direction, and means for locking each blade against movement in either direction when in neutral position with respect to the current of the stream in which the water wheel is operating.

In testimony whereof, I affix my signature.

VERNAN BAWLF.
